UNITED STATES PATENT OFFICE

WILLIAM T. AYER, OF WILMINGTON, DELAWARE, ASSIGNOR TO HERCULES POWDER COMPANY, OF WILMINGTON, DELAWARE, A CORPORATION OF DELAWARE

BLASTING CAP

Application filed December 12, 1931. Serial No. 580,557.

This invention relates to an improvement in blasting caps such as are used in the firing of commercial explosives, and more particularly relates to an arrangement whereby 5 blasting caps may be protected during shipment and storage with avoidance of accidental discharge.

As is well known, blasting caps adapted for electrical firing are equipped with a pair 10 of lead wires by which they are connected into a firing circuit after they are placed within an explosive charge to be fired. Customarily for shipment and storage of such caps the lead wires are bundled and tied 15 centrally of the bundle and with the free ends of the lead wires and the cap at opposite ends of the bundle.

The customary bundling and tying of the lead wires of such caps is ordinarily sufficient 20 to enable convenient packaging and handling of the caps, but since the cap itself is wholly unprotected, it is liable to accidental firing by any shock to which it may be subjected, as for example, by striking 25 another cap in a package, or by striking the wall of a package during shipment, from being dropped in handling, or otherwise. As will be appreciated, such caps are usually 30 loaded with fulminate of mercury, which is very sensitive and which is of great power so that the possibility of accidental firing presents a large risk.

Now, it is the object of this invention to provide 35 an arrangement whereby such caps will be adequately protected from shock, whether during shipment, in storage, or in handling, until it is desired to prepare them for use.

In accordance with this invention there 40 is provided a protector for the cap in the form of a sleeve, which is slipped over the cap and lead wires bundled in the customary manner, the protector or sleeve being retained and being made of any suitable material 45 and being retained in position at one end by turns of the end portions of the lead wires about the bundle and at the other end by bending one or more of the lengths of the bundle over the end of the protector.

Having now indicated in a general way

the nature and purpose of my invention, I will proceed to a detailed description of preferred embodiments thereof with reference to the accompanying drawing in which:

Figure 1 is a side view of a blasting cap embodying my invention.

Figure 2 is a plan view showing a blasting cap and modified form of protector for application thereto.

Figure 3 is an end view of the arrangement shown in Figure 1, the protector being of the form shown in Figure 2.

Figure 4 is a perspective view of a form of protector.

Figure 5 is an end view of the arrangement shown in Figure 1, the protector being of the form shown in Figure 4.

Referring more particularly to Figures 1, 4 and 5, A indicates a blasting cap, provided with lead wires which are bent back and forth in lengths b, b to form a bundle. In forming the bundle the lengths are arranged so that the cap A lies on the bundle roughly between the middle and one end of the bundle and a free end portion is turned about the bundle roughly at its middle acting to tie the bundle and as a stop for the protector, as will be described. The turns of the free end portion of the wires about the bundle are shown at C. 75

As is customary, the lead wires are insulated except adjacent their free ends, by which they are connected into a firing circuit. The insulated end portions of the wires are desirably shunted by means of a metal, or conducting clip D, or otherwise as by twisting together, in order to prevent accidental firing of the cap through contact of the uninsulated portions of the wires with any source of current. 80 85

The protector E is made of any suitable material, as fibre, bakelite, cloth covered metal, etc., etc., is in the form of a sleeve of a length at least equal to and desirably in excess of that of the cap. In cross section the protector or sleeve E may be generally circular, as shown in Figure 4, or it may be of any other form as, for example, polygonal. The protector will, however, be of sufficient area in cross section to slip, 90 95 100

freely or with relative ease, over the cap and bundled lead wires, into a position covering the cap and with its inner end abutting the turns D of the lead wires, as shown in Figure 1.

With the protector in the position shown in Figure 1, the end portion of a length or lengths b of the bundled lead wires is bent over the end of the protector or sleeve E to retain it in place.

Referring now to Figures 2 and 3, the protector E' is formed from a light sheet of metal f , the surfaces of which are covered with cloth g , suitably adhered thereto.

The application of the protector E' to the cap is effected by bending the protector about the cap and bundle to form a sleeve, which may be accomplished manually or by any suitable bending mechanism. The protector E' may be held in place as shown in Figure 1.

As will be obvious, the protector may be removed from the cap by simply drawing it off with the fingers and the cap may, after removal of the protector, be prepared for use as usual.

It will be understood that it is not contemplated that this invention shall be limited to details described herein for the purpose of illustration and fullness of disclosure, since it will be appreciated that various modifications in detail may be made. Thus, for example, the protector may be retained in position embracing the cap and bundle adjacent thereto by various means.

What I claim and desire to protect by Letters Patent is:

1. In combination, a blasting cap, lead wires extending from the cap and bundled therewith by bending back and forth into lengths, and a protector formed from cushioning material and loosely embracing the cap and the bundle of lead wires adjacent thereto.

2. In combination, a blasting cap, lead wires extending from the cap and bundled therewith by bending back and forth into lengths, a protector formed from cushioning material and loosely embracing the cap and the bundle of lead wires adjacent thereto and means for retaining the protector in position.

3. In combination, a blasting cap, lead wires extending from the cap and bundled therewith by bending back and forth into lengths, a free end portion of the lead wires being turned about the bundle, and a protector formed from cushioning material and loosely embracing the cap and the bundle of lead wires adjacent thereto and having one of its ends adjacent to said turns about the bundle.

4. In combination, a blasting cap, lead wires extending from the cap and bundled therewith by bending back and forth into

lengths, and a protector formed from cushioning material and loosely embracing the cap and the bundle of lead wires adjacent thereto, one of the lengths forming the bundle being bent over an end of the protector.

5. In combination, a blasting cap, lead wires extending from the cap and bundled therewith by bending back and forth into lengths, a free end portion of the lead wires being turned about the bundle, and a protector formed from cushioning material and loosely embracing the cap and the bundle of lead wires adjacent thereto, said turns acting as a stop for the protector in one direction and one of the lengths forming the bundle being bent over an end of the protector and acting as a stop for the protector in the opposite direction.

In testimony of which invention, I have hereunto set my hand, at Wilmington, Delaware, on this 9 day of December, 1931.

WILLIAM T. AYER.
